UNITED STATES PATENT OFFICE.

GEORGE M. HAYES, OF PHILADELPHIA, PENNSYLVANIA.

DESIGN FOR A CARD.

SPECIFICATION forming part of Design No. 13,869, dated April 24, 1883.

Application filed March 21, 1883. Term of patent 33 years.

To all whom it may concern:

Be it known that I, GEORGE M. HAYES, a citizen of the United States, residing in the city and county of Philadelphia, State of Pennsylvania, have invented and produced a new and original Design for a Card, of which the following is a specification, reference being had to the accompanying photographic illustration, forming part thereof.

10 The leading feature of my design for a card is a representation of the old woman in a shoe with the many children, according to the nursery rhyme, the shoe having a flap, which in one position conceals the children and in another discloses the same.

15 A represents a shoe having a flap, a, continuous thereof, adapted to be opened and closed. At the top of the shoe is a figure, b, of an elderly woman holding a fan, c, and presenting the appearance of being seated within the shoe.

20 B represents a group of children, who are represented as within the shoe beneath or behind the flap a, so that when the flap is opened the children are disclosed and when the flap 25 is shut the children are concealed. The bust of the woman appears in both positions of the flap, the effect being that when the shoe is closed the woman is peeping out at the top of the shoe and when the shoe is opened the woman is watching the children.

I claim—

1. The design for a card, consisting of a representation of a closed shoe having at top the figure of a woman. 35

2. The design for a card, consisting of a representation of a shoe with an opening and closing flap, a woman and a group of children, the flap, when shut, concealing the children, and when open disclosing the same.

GEO. M. HAYES.
